Primary Examiner — Catherine Ho*(74) Attorney, Agent, or Firm* — Wissing Miller LLP(57) **CLAIM**

The ornamental design for a label as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top view of a label showing Embodiment 1 of my new design; and,

FIG. 2 is a top view showing Embodiment 2 thereof.

The broken lines in the figures illustrate the bounds of the claimed design and form no part of the claimed design.

1 Claim, 2 Drawing Sheets
(1 of 2 Drawing Sheet(s) Filed in Color)
